UNITED STATES PATENT OFFICE.

JOHN F. O'CONNOR, OF CHICAGO, ILLINOIS, ASSIGNOR TO WILLIAM H. MINER,
OF CHAZY, NEW YORK.

HAND-BRAKE FOR RAILWAY-CARS.

1,361,484.

Specification of Letters Patent.

Patented Dec. 7, 1920.

Application filed July 21, 1919. Serial No. 312,133.

To all whom it may concern

Be it known that I, JOHN F. O'CONNOR, a citizen of the United States, residing at Chicago, in the county of Cook and State of Illinois, have invented a certain new and useful Improvement in Hand-Brakes for Railway-Cars, of which the following is a full, clear, concise, and exact description, reference being had to the accompanying drawings, forming a part of this specification.

My invention relates to improvements in hand brakes for railway cars.

The object of my invention is to provide a simple and efficient hand brake and one which shall dispense with pawl holding springs.

In the drawings forming a part of this specification, Figure 1 is an elevation of the brake embodying my invention. And Fig. 2 is a vertical section taken on line 2--2 of Fig. 1. Fig. 3 is a cross section taken on line 3--3 of Fig. 2.

In the drawings, the numeral 10 indicates a portion of a car to which the brake is attached. Rigidly secured thereto—as for instance, by the rivets 11—is a fixed housing 12 having an internal incline 13 and a circular groove 14 in its bottom member, the said groove being adapted to receive the lower flange 15 of the revolving frame 16. The housing 12 is closed at its upper end by the top plate 17 provided with the hand-hold 18 upwardly extended and internally provided with the circular recess 19, to receive the top flange 20 of the revolving frame 16. The said frame is held within the housing 12 between the member 17 and the lower wall of the fixed housing. The housing is also provided with a perforation 21 for the passage of the brake staff 22, of which only the upper portion is shown, the said brake staff having fixed thereon a ratchet 23, the upper and lower ends of which—as at 24—are provided with bearing portions and intermediate said ends having ratchet teeth 25.

The revolving frame 16 is provided with an inclined way 26 within which is received a gravity pawl 27. The said pawl is provided on its inner edge 28 with ratchet teeth which may be of any suitable number, and which are adapted to engage the teeth 25 of the ratchet, throughout their length. The gravity pawl is provided with an un-

dercut shoulder 29, downwardly extended as at 30, forming a bearing face for the tooth 31, provided upon the inner end of the operating lever 32, which is pivoted to the revolving frame as at 33. The said lever 60 is adapted to be raised and lowered as hereinafter described. The revolving frame is provided with stops 34 adapted to engage shoulders on the housing 12, as appears from an inspection of Fig. 3, to suitably 65 limit the rotation of the frame in the operation of the brake.

Between the incline 13 of the housing and the opposed inclined portion of the top plate, is formed an inclined groove 35, within which is received the gravity locking pawl 36. The said pawl is provided with a slot 37 which receives the finger 38 of the locking pawl operating arm 39, which is pivoted to the housing as at 40. The locking 70 pawl is provided at its inner edge with the teeth 41 which are adapted to engage substantially the entire length of the teeth 25 upon the ratchet. The brake described is one in which no springs are used, either in 80 connection with the operating pawl or the locking pawl. It will be noted that these pawls engage a suitable length of the ratchet, thus insuring a certain engagement and comparatively little wear.

In operating the brake, the handle 32 is elevated from its hanging inoperative position to its horizontal operative position, the tooth 31 thereon dropping, and gravity drawing the operating pawl downwardly in 90 its incline within the revolving frame until it is in engagement with the teeth of the ratchet. The handle is then swung in a horizontal plane rotating the ratchet and its shaft in a clockwise direction, as illustrated 95 in Fig. 3 of the drawings, to such extent as shall be desired and during this turning, the locking pawl will ride in and out of engagement against the teeth, the locking pawl operating handle 39 remaining stationary 100 by reason of the diagonal slot 42 shown in Fig. 2 of the drawing, which will permit the riding of the locking pawl upon the ratchet without movement of the said handle 39. Upon release of the operating pawl the 105 holding pawl will prevent the counter-rotation of the ratchet and as the lever 32, still in its horizontal position, is rotated in a contra-clockwise direction for further turning of the ratchet, the operating pawl will 110

ride back and forth upon the teeth of the ratchet and over the long inclines 43 of said teeth, this being permitted through the clearance between the end 31 of the handle 5 and the operating pawl. If it is desired to remove the locking pawl from its engagement with the ratchet, said removal can be effected through pulling upon the outer end of the lever 39, forcing the locking pawl 10 outwardly in its incline in the housing.

I claim:

1. In a hand brake the combination with a shaft and a ratchet thereon, of a housing receiving said ratchet, a revolving frame associated with the housing, a pawl mounted in said frame, the frame being provided with an inclined groove within which the said pawl moves by gravity into engagement with the ratchet 15 and is withdrawn from said engagement by the operating handle.

2. In a hand brake, the combination with a housing having a shaft therein and a ratchet mounted on said shaft, of a frame 25 swingingly mounted on said housing, said frame being provided with a downwardly inclined groove, a pawl slidingly received in

said groove, and a handle to actuate said pawl.

3. In a hand brake, in combination: the 30 casing, an incline therein, a gravity holding pawl slidingly mounted in said incline, a brake staff, a ratchet thereon within said housing, a frame swingingly mounted in the housing, a handle pivoted to said frame, the 35 said frame being provided with an incline and having a gravity pawl slidingly mounted therein to engage the ratchet, the upward movement of the pawl in said incline being effected by said handle.

4. In a hand brake for railway cars, in combination: a frame, a brake staff having a ratchet therein, means for supporting the same, the frame having a downwardly extended incline, a gravity pawl slidingly 40 mounted therein, a handle pivoted to the frame, the gravity pawl being provided with a shoulder, said handle being adapted to rotate the frame, and to elevate the pawl in the said incline.

In witness that I claim the foregoing I have hereunto subscribed my name this 14th day of July, 1919.

JOHN F. O'CONNOR.
